UNITED STATES PATENT OFFICE.

JOHN E. THOMPSON AND CLARENCE W. JAMESON, OF CHICAGO, ILLINOIS, ASSIGNEES
TO THOMPSON & JAMESON, OF CHICAGO, ILLINOIS, A CORPORATION OF ILLINOIS.

ACCELERATOR.

1,256,950.

Specification of Letters Patent. Patented Feb. 19, 1918.

Application filed October 7, 1915. Serial No. 54,625.

To all whom it may concern:

Be it known that we, JOHN E. THOMPSON and CLARENCE W. JAMESON, citizens of the United States of America, and residents of 5 Chicago, Cook county, Illinois, have invented a certain new and useful Improvement in Accelerators, of which the following is a specification.

Our invention relates to improvements in 10 motor controlling devices, and has more particular reference to that type of controlling device generally known as accelerators, used in connection with the control of elevator motors and the like.

15 One of the objects of our invention is to provide an improved device of this character which will be simple, durable and reliable in construction, and effective and efficient in operation.

20 Other objects of our invention will appear hereinafter.

Our invention consists in the features of novelty exemplified in the construction, combination and arrangement of parts herein- 25 after described, shown in the accompanying drawings, and more particularly pointed out in the appended claims.

In the drawings:

Figure 1 is a front or face view of an 30 accelerator or controlling device embodying our invention; and

Fig. 2 is a view substantially in section on the line 2-2 of Fig. 1.

The device which we have illustrated in 35 the drawings and which embodies our invention is designed more particularly for use in connection with elevator motor control, but it will be obvious to one skilled in the art, after having obtained an understanding of our invention from the disclosures herein made, that the structure may be modified or adapted for other and different use without departing from the scope and spirit of the invention.

40 The parts of the structure herein shown are mounted upon supporting board A or panel, which obviously may, if desired, form the front of a suitable box or casing containing the resistance R. We have, however, 45 simply shown the resistance R in diagram for the sake of clearness.

On the front of the supporting panel A

is a plurality or series of switches B which are arranged in a row, the switches being vertically disposed and in parallel relation. 55 Each switch has a fixed contact B¹ which in the present structure is in the form of a cylindrically-shaped piece of carbon supported in suitably shaped bracket 1 bolted to the panel A, the bolts extending through 60 the panel and carrying nuts 2 on their rear ends so as to form suitable terminals on the rear of the board to which the conductors may be attached. The carbon blocks B¹ extend forwardly from the board A and 65 their ends rest against the face of the board so as to provide a substantial backing to take the strains incident to the closing of the switch. Each contact is fastened rigidly to its bracket by a bolt 3 extending through it 70 and into the bracket. The switch arms C at their lower ends have lugs or ears so that they may be rotatably or pivotally mounted side by side in a common shaft 4. Thus they swing toward and from the fixed contacts B¹ 75 in parallel planes, which in this case are perpendicular to the plane of the panel board A. The shaft 4 is supported in proper position by a horizontally disposed bar or member 5 having outstanding projections or 80 lugs 6 at its ends in which the ends of the shaft 4 are mounted. This construction permits convenient assembling and disassembling of the switches and enables a damaged switch to be replaced without disturbing the 85 rest of the parts. The bar or member 5 is fastened to the supporting panel A in any suitable manner, and in addition to serving as a support for the switches also constitutes a conductor common to all of said switches. 90 In order, however, to insure a suitable electrical connection between each movable switch and the common member 5, we provide a flexible conductor, such as a flexible cable or strip of copper 7, for each switch. 95 These conductors 7 are connected at one end by the screws 8 to the common member 5, and at their other ends by the screws 9 to the respective switch arms C. Extending between the lower corners of the ears 6 of 100 the bar 5 is another bar 5^a which, being below the pivotal points of the switch arms, serves as a bumper bar to limit the outward or opening movement of the switches; and

in order that this limit of movement may be adjusted, we provide an adjusting screw or bolt 10 for each switch. This adjusting bolt is threaded through the bar 5^a, and is engaged by the portion 11 of the switch arm which lies below the pivotal shaft or rod 4. Each adjusting bolt may have a lock-nut 12 thereon by which it may be locked in its adjusted position. At its upper end each switch arm is broadened and formed as a sort of yoke, so as to form a substantial seat for the contact piece 13 which is held in its seat by a bolt 14 extending through the contact piece and threaded into the yoke at the upper end of the switch arm. These contact pieces 13 are cylindrical in shape and made of carbon similar to the fixed contacts B¹, and are arranged, when the switch is closed, to abut against the ends of the fixed contacts B¹. This type of contact provides a comparatively large area of conducting surface between the respective pairs of carbon pieces 13 and B¹ of each switch, and renders it practically impossible for the switches to stick or fail to open—that is, this form of contact offers no resistance to the opening of the switch. Each switch arm has another section or extension member 15 which is pivoted at 16 between the pair of lugs on the switch arm and which extends to a point below a pivotal point of the switch arm. At its lower end this extension carries a roller 17. The extension or section member in this case is yieldingly held against the switch arm C by a spiral spring 18 which bears against the section 15. This spring is held under compression between the section 15 and a nut and washer 19, carried on the end of a rod or bolt 20. The rod or bolt 20 is fastened to the lower end portion 11 of the switch arm C and extends through a suitable opening in the section 15. The nut on the outer end of the rod is adjustable thereon so as to vary the action of the spring. The arm C and the section 15 thus, in a sense, form a single arm for rotating the switch about its pivot to close it into contact with its respective fixed contact B¹, and an outward force exerted on the extension C below the pivotal point of the switch will throw the switch or spring it about its pivotal point into engagement with its respective fixed contact B¹. After it engages its contact B¹, if the force still continues the spring will yield to accommodate it. In this manner the switch is held firmly, yet yieldingly, against its contact. The switches are closed against their fixed contacts by a common actuator bar or member 21, which in the present construction moves in a plane parallel to the face of the panel board; or, stated in another way, it moves in a plane at an angle to the planes of movement of the switches. This actuator bar is so arranged

that it will engage the rollers 17 on the switch extensions 15, and by reason of a side thrust or wedging action, so to speak, on said rollers will apply a force in the direction to swing said switches into engagement with their contacts. One end 22 of the arm 70 is pivoted in a suitable bracket 23 secured to the panel board A, this pivotal connection being formed by reducing an end portion of the bar 21 and placing this reduced end portion in a suitable hole in the bracket 23. The 75 actuating member 21 is of itself operated, or may be moved, about its pivotal point in any suitable manner, but in our construction we provide a solenoid or electromagnet D of any suitable or approved type. This solenoid is 80 mounted on the panel board A and operates its core D¹ vertically. The other end of the actuator bar is pivotally connected at 24 in any suitable manner to the core of the solenoid, and is thereby swung or moved about 85 its pivot. In order that the switches may be operated successively, the actuator bar is disposed, as shown in Fig. 1, at such an angle that in swinging about its pivot it engages the roller of the switches in successive order, 90 beginning with the switch nearest the pivotal point of the actuator bar. Thus a slight movement of the actuator bar will throw in the first switch B, and a still further movement will throw in the second switch, 95 and so on until all of the switches will be thrown against their contacts. The actuator bar is rectangular, and its upper outer edge is slightly round. It is so disposed with respect to the roller that it engages the roller 100 and thrusts or forces it outward, thus closing the switch. When the switch is closed, the roller rides against the outer faces of the actuator bar while the next switch in the series is being closed, and in this manner 105 the actuator bar not only closes each switch, but holds it in closed position. The arrangement of the switches in sections which are relatively yieldable not only allows for any slight inaccuracies of manufacture and adjustment, but also reduces the effort of the solenoid to operate the switches and it also prevents the binding of the parts which would be the case if the switch arms were made rigid. This is obvious since any tendency of the actuator bar to bind when operating a switch is offset by the yielding of the lower section 15 after the switch has closed against its contact. 115

In order to govern the speed at which 120 the solenoid may actuate the actuator bar, we provide a dash pot E of any suitable or approved type. In the structure shown, the piston rod 30 of the dash pot is connected to the lower end of the solenoid core, as shown 125 clearly in the drawings, and the dash pot is provided with a suitable valve 31 to regulate its resistance to the pull of the solenoid

and thereby regulate the speed at which the solenoid actuates the switches.

The accelerator switch in this case is used for gradually decreasing the amount 5 of resistance R in the circuit of the motor. We have shown the resistance R diagrammatically. We provide a series of terminal or binding posts 32 to which the connections may be made. The various electrical 10 connections for our improved accelerator need not be particularly described except to say that they are so arranged that the switches successively shunt or short circuit portions of the resistance R included in the armature 15 circuit. We have, however, shown these connections as they are made when the accelerator is used in conjunction with the reversing switch which constitutes the subject matter of our co-pending application, Serial 20 No. 59,144, filed Nov. 1, 1915, the reversing switch and the accelerator switch being jointly used in the control of the elevator or other motor. It is, of course, understood 25 that our improved accelerator may be used alone or in conjunction with other types of reversing switches without departing from the scope and spirit of our invention.

What we claim as our invention is:

1. The combination of a supporting panel 30 having a plurality of contacts, a plurality of pivotal switch arms coöperating therewith and movable toward and from said contacts, and a common actuator member pivotally mounted at one end and movable in a 35 plane transverse to the plane of movement of said switch arms and arranged to successively engage and actuate said arms and means for swinging said bar about its pivot.

2. The combination of a support, a plurality 40 of switches thereon arranged side by side and movable in parallel planes, a bar pivoted at one end on said support and arranged adjacent said switches and movable in a plane at an angle to the planes of movement of said switches to engage the switches 45 and operate them, and electromagnetic means connected to the other end of said bar for moving said bar about its pivot.

3. The combination of a switch comprising 50 pivotally connected relatively yieldable sections, a contact with which one of the sections coöperates, and a movable cam bar pivoted at one end and arranged to engage the other section of said switch to close the 55 switch against its contact.

4. The combination of a pivotally mounted 60 switch arm, a contact with which the switch arm engages, a yielding extension on said switch, a bar pivoted at one end and movable about its pivot to engage said yielding extension and close the switch against its contact, and means for actuating said bar.

5. The combination of a plurality of relatively fixed contacts, a plurality of pivoted 65 switches movable toward and from said contacts, a yieldable extension on each switch extending beyond the pivot of said switch, a bar pivoted at one end and movable about its pivot in a plane transverse to the planes 70 of movement of said switches, and an electromagnet for moving said bar successively into engagement with said extensions to force the switches against their contacts.

6. The combination of a plurality of fixed 75 contacts, a plurality of pivoted switches forming levers adapted to move to and from said contacts, and each comprising yieldably related sections having portions extending beyond their pivots, a pivoted cam bar 80 angularly disposed with reference to the projecting portions of said switch levers and adapted when moved about its pivot to successively engage said projecting portions and close the switches, and an electromagnet 85 for moving said cam bar about its pivot.

7. The combination of a plurality of fixed contacts, a plurality of pivoted switches forming levers adapted to move to and from 90 said contacts, and each comprising yieldably related sections having portions extending beyond their pivots, a pivoted cam bar angularly disposed with reference to the projecting portions of said switch levers and adapted when moved about its pivot to successively engage said projecting portions 95 and close the switches, an electromagnet for moving said cam bar about its pivot, and limit stops for normally holding said switches in proper position with respect to said cam bar. 100

8. The combination of a supporting panel, a plurality of fixed contacts on said panel, a plurality of switch levers freely movable toward and from the contacts, each switch lever comprising pivotally related sections, 105 a cam bar pivoted at one end on said supporting panel and disposed at an angle to the ends of said switch levers so that when swung about its pivot it will successively engage the ends of said levers and force 110 them into engagement with their fixed contacts, and spring mechanism between the sections of each lever, adapted to yield to the action of the cam bar when the switches are in engagement with their contacts. 115

9. The combination of a supporting panel, a plurality of fixed contacts thereon, a plurality of switch levers movable in parallel planes toward and from said contacts, a common bracket on said panel having a rod 120 common to all of said switches and forming a pivot therefor, an extension arm pivoted on each switch and extending below said pivot rod, a bar pivoted on said panel and disposed at an angle to the ends of said extensions so that when moved about its pivot 125

it will successively engage said extensions and swing the switches into engagement with their fixed contacts, a spring normally holding the extension in the path of the bar and adapted to yield to the action of the bar when the switch engages its fixed contact, and an electromagnet for actuating said bar.

Signed by us at Chicago, Illinois, this 2nd day of October, 1915.

JOHN E. THOMPSON.
